REFRIGERATING MECHANISM

Edwin M. Post, Jr., New York, and George O. Hanshew, Forest Hills, N. Y., assignors to International Motor Company, New York, N. Y., a corporation of Delaware

Application August 3, 1932, Serial No. 627,310

1 Claim. (Cl. 62—6)

The present invention relates to refrigerating mechanisms and embodies, more specifically, an improved device for maintaining a predetermined temperature within a compartment. More particularly, the invention embodies a refrigerating device whereby the temperature of a compartment is controlled by means of a circulating system to direct air from the compartment about a cooling medium and reintroduce such air into the compartment. In this connection, the present invention has been designed for use in connection with a refrigerating medium, such as solid carbon dioxide, the temperature of which is considerably below the temperature at which it is desired to maintain a compartment. To utilize such a substance as a refrigerant and effectively control the temperature of the compartment has proved to be an extremely difficult matter and the present invention therefore has for an object the provision of a refrigerating mechanism in which substances, such as solid carbon dioxide, may be used, such mechanism having means for effectively controlling the temperature of a predetermined compartment.

A further object of the invention is to provide a refrigerating mechanism of the above character wherein air within a compartment is maintained in an agitated or circulating state in addition to providing means for effecting a predetermined temperature control thereof.

A further object of the invention is to provide a refrigerating mechanism of the above character wherein the refrigerant used is maintained in a suitable insulated and protective compartment separated from the compartment to be refrigerated, a circulating mechanism being further provided to effect a desired circulation of air between the compartments.

Further objects, not specifically enumerated above, will be apparent as the invention is described in greater detail in connection with the accompanying drawings, wherein:

Figure 1 is a view in vertical section taken on the broken plane indicated by the line 1—1 of Figure 2, and looking in the direction of the arrows.

Figure 2 is a view in horizontal section, taken on the plane indicated by the line 2—2 of Figure 1, and looking in the direction of the arrows.

Figure 3 is a plan view of a motor vehicle body or other compartment constructed with a refrigerating mechanism in accordance with the present invention.

Figure 4 is a view in side elevation showing the device of Figure 3.

Figure 5 is a diagrammatic representation of a modified form of refrigerating mechanism constructed in accordance with the present invention.

Figure 6 is a view in vertical section taken through a thermostatic relay constructed in accordance with the present invention.

Figure 7 is a plan view, showing the relay of Figure 6.

Figure 8 is a diagrammatic representation of an electrical system which is adapted to operate the refrigerating mechanism shown in Figures 1 and 2.

Figures 9, 10, and 11 are detail views in section, taken on lines 9, 10, and 11, respectively, of Figure 8 and looking in the direction of the arrows.

Figure 12 is a diagrammatic representation of an electrical system which is adapted to operate the form of invention shown in Figures 3, 4, and 5.

With reference to the above drawings, a refrigerating compartment is shown at 10, the compartment being formed by a cabinet 11 of suitable insulating material. Associated with the refrigerating compartment is an auxiliary compartment 12 within which a refrigerant 13 is adapted to be received, the compartment 12 being separate from and not in communication with compartment 10. The two compartments are separated by a plate 14 which may be formed upon opposite sides of a partition 15 within a circulating compartment 16. The circulating compartment 16 may be formed by a partition 17 of suitable insulating material which is provided with openings 18 and 19 at the top thereof.

A funnel-shaped conduit 20 is secured over the opening 18 and thus directs air to such opening and into the circulating compartment 16 from a fan 21. The path of air passing through opening 18 is indicated by the long solid arrows of Figure 2 and the dotted arrows of Figure 1.

When the air passes through opening 18, it passes downwardly between the parallel webs 14' upon plate 14 and upwardly upon the other side of partition 15 as indicated by the solid arrows of Figure 1. After passing upwardly through the circulating chamber 16, the air passes out through aperture 19 into the refrigerating chamber 10. A baffle 22 is provided to prevent a circulating fan 23 from circulating air over the cold element.

In order that the air within the refrigerating compartment 10 may not stagnate and to prevent the formation of air pockets within such compartment, the circulating fan 23 is provided therein, such fan serving to maintain a desired circulation of air within the refrigerating compartment 10.

In order that the refrigerant 13 may be maintained against the plate 14, a backing plate 24 is mounted upon a rod 25 which is slidably mounted within a cover 26 of chamber 12. The outer end 5 of rod 25 is provided with a pulley 27 over which a flexible cord 28 passes to support a weight 29 at the end thereof. Guide pulley 30 upon the cover 26 serves to guide the movement of the flexible rod and the latter is anchored at 31 to the upper portion of the cover 26. In this fashion, plate 24 is urged inwardly to maintain the block of refrigerant 13 against plate 14.

When the temperature within the chamber 10 rises to a predetermined maximum a thermostat 32 functions to rotate the fan 21 and circulate air from the refrigerating chamber 10 through the circulating chamber 16. This causes the air circulated through chamber 16 to be chilled as it passes over the plate 14 and between the webs 14', thus bringing the temperature within the refrigerating chamber down to a predetermined value. By forming the plate 14 in webs 14' of a suitable heat conducting material an effective heat transfer is obtained between the refrigerant 13 and the 20 air circulated within chamber 16. Inasmuch as the registering chamber 10 is isolated from the refrigerant, the temperature within such chamber may be effectively controlled.

With reference to Figures 3 and 4, a refrigerating chamber is illustrated as being the interior of a vehicle body 33. This body is formed with an upper outlet duct 34 and lower inlet ducts 35. The ducts 35 may extend around and about the bottom of the body and communicate with a duct 36 which is connected to a circulating fan 37. Fan 37 directs air from the ducts 35 and 36 to a valve chamber 38 within which a valve 39 is mounted. When the valve is moved into a vertical position, as illustrated in Figure 4, air is circulated from the fan 37 through the right hand portion of the valve chamber and under a plate 40 from which webs 41 extend. A transfer partition 42 is provided to direct the air to flow outwardly along a portion of the webs 41 and plate 40 and back upon the other side thereof as illustrated in Figure 3. After emerging from beneath the plate 40 and webs 41, the air flows into the left hand portion of the valve chamber 38, as viewed in Figure 4, from whence it flows into a duct 43 to a duct 44 which communicates with the outlet duct 34. When the temperature within the body is decreased to a predetermined minimum, a thermostat mounted therein functions to move the valve 39 into a horizontal position, as indicated in dot and dash lines in Figure 4. The resulting flow of air from the fan 37 is through the upper portion of the valve chamber 38 and directly into the duct 43, thereby eliminating the circulation chamber beneath plate 40. The refrigerating effect may be derived from a refrigerant 45, indicated in dot and dash lines in Figure 4, the refrigerant being introduced into the chamber above plate 40 through one wall of the vehicle body.

In the construction shown in Figure 5, a modified form of the invention is illustrated wherein a supply duct is shown at 46 to direct air from a circulating compartment 47 to a refrigerating compartment, parallel ducts 48 and 49 being provided to remove air from the refrigerating chamber. A circulating fan 50 may be placed in the duct 46 and duct 48 is connected directly to duct 46 while duct 49 communicates with the circulating passage 47 and is connected to the duct 46 through a duct 51. Valves 52 and 53 are mount-

ed in the ducts 48 and 51, respectively, being actuated by a motor 54 and so constructed that one is in opened position when the other is closed. A compartment 55 is formed above a plate 56 from which webs 57 depend, a refrigerant indicated at 58 being inserted within the compartment 55 in order that the air circulating beneath the plate 56 and about the webs 57 may be cooled.

Successive actuations of motor 54 will be seen to close one of the ducts 48 and 51 while the other 10 one is open. In this fashion an effective temperature control within the refrigerating chamber is afforded, the circulation of air within the refrigerating chamber being accomplished by the same motor that effects circulation thereof about 15 the refrigerant.

With reference to Figures 6 and 7 the thermostatic element for controlling the air circulating mechanism in accordance with the present invention is illustrated. This mechanism shown 20 generally in Figure 1, includes a coiled heat responsive element 58, one end of which is mounted upon a tubular member 59 and the other end of which is secured to a spindle 60. Spindle 60 is journaled upon a cone bearing 61 which is formed 25 upon a set screw 62, adjustably mounted upon a bracket 63 within the refrigerating chamber. The other end of the spindle 60 is secured to a thermal insulating shaft section 64 which is provided with a rounded shaft section 65 within an 30 insulating sleeve 67, mounted within the wall 11 of the chamber 10. Insulating sleeve is secured at the lower extremity to tubular member 59 and the base 68 of bracket 63.

A mounting plate 69 is secured to the sleeve 67 35 and provided with an adjustable plate 70 which may be connected thereto by means of screws 71 which extend through elongated arcuate slots 72 formed in the plate 70. In this fashion, relative movement between the plates 69 and 70 is 40 accommodated and the position of the plates with respect to each other thus rendered adjustable. Upon plate 70 an upwardly extending bracket is formed, this bracket supporting a set screw 73 within which the end of shaft section 45 65 is journaled. Shaft section 65 has mounted thereon an armature 74 which is disposed adjacent electro-magnets 75 and 76, respectively. The electro-magnets 75 and 76 are mounted upon brackets 77, upon plate 70, and thus may be suitably positioned opposite the ends of armature 74. Upon a variation in temperature within the chamber 10, the thermal element 58 expands or contracts and moves armature 74 into contacting position with terminals 78 and 79 upon the 50 respective magnets 76 and 75. With reference to Figure 8, the electrical circuits for effecting the operation of the mechanism are illustrated in detail. In the interest of clearness the thermal element is illustrated in a simplified fashion. 60 Magnets 76 and 75 are shown as being positioned in opposed relationship, each being connected to suitable contacts upon a contacting mechanism 80 by means of wires 81 and 82, respectively.

The thermal element 32 is connected through 65 a wire 83 and switch 84 to a battery 85 or other source of electrical energy, the other terminal of battery 85 being connected to the base of the contacting mechanism 80 by means of a wire 86. Fan 21 is connected in an electrical circuit 87 70 which is connected to battery 85 through a switch 88. Fan 23 is connected through a circuit 89 and switch 90 to the battery 85.

The contacting device 80 includes a motor 91 which is geared to a shaft 92 journaled in bear- 75

ings 93 upon the base of the device. Upon shaft 92, cams 94 and 95 are mounted, as well as a contacting disc 96. Spring contact fingers 97, 98 and 99 bear upon the respective members 94, 95, 5 and 96, spring contact member 97 being connected to wire 81 while member 98 is connected to wire 82 and member 99 is connected through a wire 100 to the motor 21.

The spring contact fingers are mounted upon 10 an insulating plate 102 which is suitably secured to the base of the device 80, by brackets 103. Cams 94 and 95 are provided with insulating segments 104 while disc 96 is provided with an insulating disc 105. Wires 106 and 107 connect 15 motor 91 across wires 81 and 82.

The electrical system functions in the following manner. Fan 23, of course, is continuously operated to agitate the air within the refrigerating device. Fan 21 is controlled by contact disc 20 96, and when finger 99 engages the conducting segment 105 the fan is driven by its power source. When shaft 92 turns the disc 96 to place a conducting portion of the disc under the finger 99 the motor 21 is grounded through battery 85 and the 25 motor is operated. Rotation of shaft 92 is controlled by cams 94 and 95 which are connected with the respective terminals 78 and 79. When the temperature within the refrigerating device 30 rises to a predetermined value, one of the terminals 78 and 79 is contacted by the thermal element 32. For example, if the thermal element 32 engages contact 78, battery 85 is connected to wires 81 and 106. It is assumed that finger 97 rests upon the insulating segment 104 of cam 94 35 and therefore finger 98 will rest upon a conducting portion of cam 95. The motor 91 will thus be grounded through wire 107, wire 82, finger 98, and cam 95 to the frame of the device 80. Consequent rotation of shaft 92 by motor 91 40 causes the insulating segment 105 to pass under finger 99 and place the latter upon a conducting portion of the disc 96. This causes motor 21 to operate, circulating air from the refrigerating compartment around the refrigerant. As soon as 45 finger 99 rests upon a conducting portion of disc 96, finger 98 drops off of the cam 95 and rests upon the insulating segment 104 thereof. This disconnects motor 91 from the battery and therefore stops the rotation of shaft 92. During this 50 operation finger 97 has passed from the insulating section 104 of cam 94 to a conducting portion thereof so that when the thermal element 32 engages contact 79 upon a predetermined fall in temperature within the refrigerating chamber 55 the motor will again be actuated to place finger 99 upon the insulating segment 105.

In the system illustrated by the diagram shown in Figure 12, the motor 50 is connected to the battery as described in connection with motor 23. Instead of providing a fan and fan motor 21, motor 54 is connected to a disc 96, motor 54 being of a stop type such as a solenoid, or electro-magnet. Inasmuch as the electrical elements of the system shown in Figure 12 are similar to those shown in Figure 8, a detailed description thereof is deemed unnecessary, the operation of such sys-

tem being obvious from the description of the operation of the system shown in Figure 8. Instead of providing an additional fan, such as fan 21, the motor 54 is operated to cause air from the refrigerating chamber to be circulated either through duct 48 or duct 49 and duct 51. When valve 52 is in the position shown in Figure 12, the refrigerating element 58 is not functioning and air is merely circulated through the refrigerating compartment by the motor 50. When 10 valves 52 and 53 are moved to the position shown in Figure 5, however, the circulation of air through duct 48 is prevented and motor 50 directs air through ducts 49 and 51, passing through the circulating chamber 47 to cause the refrigerating 15 element to function.

By providing magnets 15 and 76 in the circuit of the thermal element a quick make and break is insured, element 32 being maintained against the respective contacts 78 and 79 until the circuit 20 therethrough is broken through cams 94 or 95. Provision for the adjustment of thermal element 58 is provided since plates 69 and 70 may be relatively rotated. This moves the elements upon which the ends of thermal element 58 are secured 25 to place a desired initial tension upon the element.

It will be seen that the motor 54 may be dispensed with and the valves actuated by a direct connection with shaft 92. Furthermore the cams 30 95 need not have shoulders but may be discs or other circuit breaking devices of well known form.

From the foregoing it will be seen that a refrigerating mechanism has been provided which functions effectively not only to preserve a predetermined temperature within a refrigerating compartment but also to maintain a desired circulation of air within the compartment.

In the embodiment described herein, the invention has been described in connection with a refrigerating mechanism. Inasmuch as the mechanism is essentially a heat transfer mechanism, instead of being embodied in a refrigerating device, it may be utilized in connection with mechanisms wherein it is desired to supply heat to 40 a compartment and maintain the same at a predetermined temperature.

While the invention has been described with specific reference to the accompanying drawings, it is not to be limited, save as defined in the appended claim.

We claim as our invention:

A heat interchange device comprising a refrigerating chamber, a circulating chamber isolated from the refrigerating chamber, the circulating 55 chamber communicating with the refrigerating chamber through two ports adjacent the top thereof, a heat interchange device in the last named chamber, a heat responsive element in the first chamber, mechanical means offset with respect to the ports to agitate positively the air within the first chamber, and mechanical means juxtaposed with respect to one of the ports and controlled by the heat responsive device for causing air to be circulated between the said chambers. 60 65

EDWIN M. POST, JR.
GEORGE O. HANSHEW.
